WARP TENSION LET-OFF DEVICE
FOR LOOMS

Louis Ritsky, Philadelphia, Pa.

Application April 22, 1952, Serial No. 283,563

6 Claims. (Cl. 139—100)

1

This invention relates to warp tension let-off devices for looms, and has for its primary object the provision of a device of this character which will maintain the warp at proper tension while permitting the required intermittent rotation of the warp beam and draw-off of the warp threads, and will act to halt the rotation of the warp beam as required.

In known loom construction, it is common practice to tension the warp beam by the use of a band extended about and frictionally engaging a drum on the warp beam, and one or more suspended weights usually serve to apply pull on the band to thereby cause the same to be held frictionally against the drum. Aside from other objections possessed by such an arrangement, there is the objection that it tends to obstruct the rear of the loom and makes it practically impossible to employ more than one row of warp beams.

It is therefore an object of the present invention to provide a device of the character described in which the use of tension-applying weights is obviated; in which the warp beam will be permitted to rotate when required under the pull of the warp threads, and in which an automatic braking and application of tension will be at once applied as the rotation of the warp beam is ceased.

More particularly, the invention contemplates the provision of a warp beam provided with a drum carrying a plurality of brake band segments which are pivotally and adjustably connected at one end and have a lever or pry bar pivotally connected to one of the segments and interposed between the segments and arranged to operate with other elements to allow the segments to be brought toward one another into brake-application position as soon as the pull of the warp thread ceases, whereby an immediate braking effect on the warp beam occurs. As will appear hereinafter, this arrangement is such as to permit rotation of the warp beam as required, and an immediate application of braking and tensioning force when the rotation of the warp beam ceases.

In the accompanying drawing, wherein an illustrative embodiment of the invention is disclosed, Fig. 1 is a top plan view of the improved structure; Fig. 2 is a sectional view taken substantially on the line 2—2 of Fig. 1, looking in the direction of the arrows, showing the braking device in released position, and Fig. 3 is a view similar to Fig. 2, but showing the device in applied position but with the free end of the lever raised off the stop pin in order to show construction.

2

Referring to the drawing, 1 indicates the warp beam, carrying the conventional warp threads 2, which are drawn downwardly from the warp beam as seen in Fig. 2. The shaft 3 of the warp beam is rotative in suitable bearings 30 and carries a drum 4 having its periphery embraced by the brake segments 5 and 6, each of which is provided with the conventional brake lining 7, frictionally operative against the periphery of the drum 4. At one end, the segment 5 is provided with a projecting lug 8, which is pivotally and threadably engaged with an adjusting screw 9. A similar projecting lug is provided on the segment 6, as indicated at 10 and the same is also pivotally and threadably engaged with the adjusting screw 9. This arrangement is such as to enable the two segments to be adjusted relatively to one another to thereby engage the drum 4 with the required braking force.

At its opposite end, the segment 5 is provided with a lug 11 and a similar lug, shown at 12, is provided on the segment 6. A pin 13 extends through the lugs 11 and 12, and between the lug 11 and a nut 14 and a washer arranged on one end of the pin 13 is a coil spring 15. A similar coil spring 16 surrounds the pin 13 between the lug 12 and the nut 17 and its washer. By adjustment of the nuts 14 and 17 on the opposite threaded ends of the pin 13, the pressure of the springs 15 and 16 can be regulated so that the braking force will be applied to the required degree when required.

At 18 is shown a lever or pry-bar which has a downwardly-bent end or tip 19 fitting into an aperture 20 provided in the lug 12. The lever 18 is also provided with an aperture 21 extending through it to permit the passage of the pin 13. Near its free end, the lever or pry-bar 18 is provided with an aperture 22 adapted to fit over a projecting pin 23 extending rigidly upwardly from a portion 24 of the frame of the loom. A compression coil spring 25 surrounds the pin 23 and is supported upon the portion 24 of the frame.

From the foregoing, the operation of the improved let-off device will be readily understood. The normal position of the device is that shown in Fig. 3, except that the end of the lever will be actually fitted on the pin 23, at which time the warp beam is stationary, and the segments 5 and 6 are applying braking pressure upon the drum 4 under the pressure imparted to the segments by the springs 15 and 16. At this time the lever 18 has its free end slightly elevated to an extent to be free of any elevating pressure on said end 55 of the lever by the spring 25. Hence the bar 18 does not at this time interfere with the tendency of the lugs 11 and 12 to be urged toward one an-

other under the pressure of the springs 15 and 16. As a pull is exerted on the warp threads 2, the warp beam will begin to rotate in a counter-clockwise direction and such rotative movement will bring the free end of the lever 18 downwardly along the pin 23 and forcibly against the spring 25 which will then act as a stop or stop element, until a prying action will be imparted to the lever 18, as shown in Fig. 2, causing the lugs 11 and 12 to be pried apart by said lever, as clearly seen in Fig. 2, to tend to separate the segments 6 and 7 and thus release the braking force upon the drum 4 and permit rotative movement of the warp beam 1 under the pull of the warp threads. As long as the pull of the warp threads is exerted, the lever 18 will remain in its prying position as shown in Fig. 2 and the brake segments remain in the unapplied position of Fig. 2.

As soon as the pull on the warp threads is discontinued, the holding down of the lever 18 on the spring 25 will cease, and the lever will then lift and assume an elevated position ceasing its prying action and permitting the springs 15 and 16 to at once become active to draw the segments 5 and 6 toward one another and to apply their lined faces frictionally against the drum 4 and halt further rotative movements of the warp beam. It will be understood that lever 18 never actually rises off the pin 23 as shown in Fig. 3, such position being shown merely to indicate the manner in which the braking elements are supported solely on the drum 4.

Thus the lever 18 may be fulcrumed at any suitable place on the frame or even on the floor supporting the machine, the main object being to leave the rear of the loom unobstructed.

From the foregoing, it will be apparent that the operation of the device is quite automatic, with the release of the braking force taking place by the pull of the warp threads and the braking force and slack take-up immediately applied upon the cessation of the pull upon the warp beam by the warp threads.

Having described one embodiment of the invention, it is obvious that the same is not to be restricted thereto, but is broad enough to cover all structures coming within the scope of the annexed claims.

What I claim is:

1. In a loom, a rotative warp beam, a drum carried thereby, a plurality of brake band segments overlying the drum, the segments being adjustably connected at one end, the opposite end of each segment being provided with a lug, spring means for urging the lugs toward one another, a lever interposed between the lugs and connected to one of said lugs, and a stop element for the lever adapted to incline the lever when the warp beam is under pull of the warp threads to thereby cause the lever to pry the lugs apart to release pressure of the brake band segments on the drum.

2. In a loom, a rotative warp beam provided with a drum, a pair of brake band segments overlying the drum, spring means normally operative upon said segments to urge the same into frictional braking contact with the drum, a lever having an end portion interposed between parts of the segments and adapted when inclined to pry the segments apart, and a stop element adjacent to the warp beam for engaging an end portion of the lever to thereby cause inclination of the lever into segment-prying position, when the warp beam is rotated by pull of the warp threads.

3. In a loom, a rotative warp beam provided with a drum, a pair of brake band segments over-

lying the drum, the segments being pivotally and adjustably connected together at one end, each segment being provided with a projecting lug at its opposite end, spring means operative upon the lugs for normally urging the same toward one another to maintain the segments in braking position, a lever having an end portion pivotally connected to one of the segments, said end portion being disposed between the segments, and a stop for the opposite end of the lever adapted to cause the portion of the lever that is interposed between the lugs to pry the lugs apart when the lever is held in engagement with the stop by the pull of the warp threads.

4. In a loom as provided for in claim 3, where-in the spring means is mounted on a pin extending through the lugs, the lever having an aperture through which said pin passes, and the stop includes a spring against which the lever is held when the warp beam is rotated by pull of the warp threads.

5. In a loom, a rotative warp beam, a drum on the warp beam, a pair of brake segments overlying the periphery of the drum, an adjusting screw threadably and pivotally connected to one end of each of the segments, each of the segments being provided at its opposite end with a lug, a pin extending through the lugs, springs surrounding the pin and normally operative to force the lugs toward one another and to urge the segments into braking contact with the drum, a lever having an end portion disposed between the lugs, said lever having an aperture through which the pin passes, the end portion of the lever having a downturned tip entering an aperture in one of the lugs, the lever having a free end provided with an aperture, a frame element provided with an upstanding pin surrounded by a coil spring, said pin being adapted to fit within the aperture in the free end of the lever and the lever held against the coil spring while the warp beam is rotated under the pull of the warp threads to thereby cause the portion of the lever that is located between the lugs to exert a prying action on said lugs to force the same apart and retain the segments in released position as long as pull is exerted on the warp threads.

6. In a loom, a rotative warp beam, braking means therefor consisting of a pair of segments normally held in braking position while the warp beam is stationary, and a prying element having a part interposed between the segments, means for engaging said prying element when the warp beam is rotated under pull of the warp threads, to thereby pry the segments apart and retain them in released position as long as warp thread pull is imposed on the warp beam.
